DESIGN FOR A LAMP OR SIMILAR ARTICLE

Howard Asch, New York, N. Y.

Application June 1, 1945, Serial No. 119,844

Term of patent 3½ years

(Cl. D48—20)

To all whom it may concern:

Be it known that Howard Asch, citizen of United States, and resident of New York city, in the county of New York and State of New York, has invented a new, original, and ornamental Design for a Lamp or Similar Article, of which the following is a specification, reference being had to the accompanying drawing, forming part thereof, and in which the single figure is a front perspective view of a lamp or similar article embodying my new design.

I claim:

The ornamental design for a lamp or similar article, substantially as shown.

HOWARD ASCH.
